UNITED STATES PATENT OFFICE

148,467

DESIGN FOR A DUAL CROSS COMMUNION SET

Delphus Goudreau, Northbridge, Mass.

Application April 14, 1947, Serial No. 138,392

Term of patent 3½ years

(Cl. D29—23)

To all whom it may concern:

Be it known that Delphus Goudreau, a citizen of the United States, residing at Northbridge, in the county of Worcester and State of Massachusetts, has invented a new, original, and ornamental Design for Dual Cross Communion Sets, of which the following is a specification, reference being had to the accompanying drawing, forming part thereof.

The characteristic feature of my invention resides in the contrasting inserts in the ends of the arms of the dual cross.

Fig. 1 is a top plan view;

Fig. 2 is a view in front elevation; and

Fig. 3 is an edge view of the dual cross communion set showing my new design.

I claim:

The ornamental design for a dual cross communion set, as shown and described.

DELPHUS GOUDREAU.
